UNITED STATES PATENT OFFICE

133,352

DESIGN FOR A SEAT SPRING UNIT

Edward W. Schlappritz, Minneapolis, Minn.

Application April 8, 1942, Serial No. 106,491

Term of patent 14 years

To all whom it may concern:

Be it known that I, Edward W. Schlappritz, a citizen of the United States of America, residing at Minneapolis, in the county of Hennepin and State of Minnesota, have invented a new, original, and ornamental Design for a Seat Spring Unit, of which the following is a specification, reference being had therein to the accompanying drawing, forming a part thereof, wherein:

Figure 1 is a perspective view of a seat spring unit, showing my new design;

Figure 2 is a side elevational view; and

Figure 3 is an end elevational view thereof.

I claim:

The ornamental design for a seat spring unit, substantially as shown.

EDWARD W. SCHLAPPITZI.
